UNITED STATES PATENT OFFICE.

FRANK HINDS, OF HUDSON FALLS, NEW YORK.

DOOR HOLDER.

Application filed June 9, 1925. Serial No. 36,023.

My present invention has reference to a door holding device for carpenters' use.

My object is the provision of a device of this character comprising a base having impinging elements associated therewith whereby the same may be secured on the floor surface, said base being provided with a central notch and having adjustably secured on its upper face angle members or knees movable toward or away from the notch to effectively grip a door therebetween, so that the edges of the door may be planed, the door may be held for notching one edge thereof for the hinges and also, after the door is hung, the same may be sustained from swinging when being mortised for locks.

The drawing which accompany and form part of this application illustrate a satisfactory embodiment of the improvement, and wherein:

Figure 1 is a front elevation of the improvement with parts in section.

Figure 2 is a top plan view thereof.

Figure 3 is a sectional view on the line 3—3 of Figure 1.

Figure 4 is a perspective view of one of the knees.

My improvement may be constructed of any desired material and includes a comparatively wide base 1 having a straight edge. This edge is centrally notched, as at 2. The notch is of a width to receive therein doors of varying thicknesses. The base has its second edge rounded, and said base adjacent to the said rounded edge is provided at spaced intervals with openings 3 through which pass removable impinging elements 4. The impinging elements may be in the nature of short headed nails and may be forced in a floor surface by the employment of a hammer. Again the impinging elements may be integrally formed on the base 1. The base 1, in line with its straight edge and to the opposite side of the

notch 2 therein, is provided with upstanding threaded elements 5. These elements 5 pass through elongated slots 6 in the base portions 7 of angle members. The vertical flanges of the angular members are indicated by the numerals 8 and a connecting brace between the portions 7 and 8 of the said angle members is indicated by the numeral 9. The angle members are commonly termed knees. Arranged over the threaded elements or bolts 5 there are washers 10 that are contacted by winged nuts 11 that are screwed on the bolts. By such arrangement it will be noted that the knees may be moved toward and away from each other to firmly grip therebetween a door when the latter is arranged in the notch 2. On the base in a line with the rear wall provided by the notch 2 there is an upstanding reinforcing rib or lug 12.

The simplicity of my construction and the advantages thereof, will, it is thought, be perfectly apparent to those skilled in the art to which such inventions relate and a more detailed description is not believed necessary.

Having described the invention, I claim:

In a device of the character described, a base member having a straight edge formed with a centrally disposed notch, angle knees arranged on the base in alignment with the straight edge thereof and disposed upon opposite sides of the notch, the base portions of said angle knees being formed with longitudinal slots, upstanding threaded elements carried by the base and disposed within said slots, a wing nut upon each threaded element, a reinforcing rib at the front of the base and extending transversely of the notch portion and impinging elements carried by the base.

In testimony whereof I affix my signature.

FRANK HINDS.
